UNITED STATES PATENT OFFICE

NOAH H. COLE, OF GROVE CITY, PENNSYLVANIA

BOX QUILT

Application filed August 7, 1929. Serial No. 384,222.

This invention relates to what may be termed a quilt, having as its primary object the provision of a suitable frame structure adapted to be supported upon a bed, couch or the like for completely enshrouding the occupants of the bed and a suitable material stretched within the frame for the purpose of protecting the occupants from mosquitos, flies and the like, the same also being capable for serving as a support for the bed clothes so that the occupants of the bed may be covered by the bed clothing, and at the same time prevent the bed clothing from coming into contact with the occupants.

Another object of this invention is to provide a suitable frame structure adapted to be disposed about a bed for support by the bed to act as a guard for the occupants of the bed as a protection to the sleepers from flies, mosquitos and the like, and which is so adapted for association with the bed as to be capable of use of supporting the bed clothing about the sleeper and at the same time to keep the weight of the bedding from the bodies of the sleepers, a device of this nature being of particular advantage in the case of a person who has just undergone a surgical operation such as appendicitis or other operation of similar nature.

Other objects and advantages of this invention will become apparent during a study of the following description, taken in conjunction with the drawings, wherein:

Figure 1 is a top plan view of my invention.

Figure 2 is a bottom plan view of the same and showing the device in a collapsed or folded position.

Figure 3 is a transverse vertical sectional view taken through the device.

Figure 4 is a fragmentary detail perspective view of one corner of my device, with the top piece broken away.

Figure 5 is a fragmentary detail perspective view of a bottom view of the device at one corner thereof, and showing the same in a folded position.

Referring more in detail to the drawings, it will be seen that my improved quilt or protecto

consists generally by the reference character 5, side sections 6 and end sections 7. The side and end sections are hingedly connected to the top section 5, the end sections being adapted to fold inwardly toward one another for rest upon the top section 5, and the side sections inwardly toward one another for disposition upon the end sections so that when said device is in a folded position, a compact structure is attained which may be easily moved from place to place and which may be placed in any out of the way position without utilizing needed space.

Each of the sections comprises a frame and a wire screen, the top section 5 including side members 5' provided with inwardly directed flanges 10, and end members 5'' provided with inwardly directed flanges 11. The screen 12 of the top section 5 is secured to the flanges 10, 11 through the medium of cleats 13 (see Figure 5).

Each of the side sections 6 include frame members 6' connected by frame members 6'', and the screen 12'' is fastened to the members 6', 6'' through the medium of cleats 22 (see Figure 5).

As also shown in Figure 5, each of the end sections 7 include frame members 7'' provided with inwardly directed flanges 14, and frame members 7' provided with inwardly directed flanges 15. The screen 12' is secured to the flanges 14, 15 through the medium of cleats 16.

One member 6' of each side section 6 is hinged to a member 5' of top section 5 by hinges 19, the leaves of which are bolted or otherwise secured to the referred to member 6' and 5', as at 21 and 20 respectively.

One member 7'' of each end section 7 is hinged to a member 5'' of top section 5 through the medium of hinges 17 one flange 18 of which is bent angularly so that when the sections 7 are swung outwardly at right angles to the section 5, the hinged members 7'' will contact the edges of the adjacent members 5'' for limiting swinging movement of the sections 7 (see Figure 4).

Thus, and as also shown in Figure 4, when the device is set up for use, and the sections 6 and 7 are swung outwardly to the position

- suggested in Figure 4, it will be apparent that the members 6'' of the sections 6 contact the adjacent members 7' of the sections 7, while the members 6' of sections 6 will abut 5. the edges of the adjacent members 5', so that obviously the sections 6 and 7 provide a suitable support for the top section 5, and at the same time sections 6 and 7 provide side and end walls for the device.
- 10 Completing the structure of the top section 5, are cross strips 23 connecting the members 5' and a longitudinal strip 24 connected to the members 23 and to the members 5''.

15 Each of the side sections 6 have their oppositely disposed members 6' connected by cross members 26, while each of the sections 7 have their oppositely disposed members 7'' connected by cross strips 27.

20 The device when in its extended position is adapted to be disposed over a bed, couch or the like, the top section 5 covering the entire area of the bed, and the sides and end sections have their lower edges respectively disposed between the side and ends of the bed 25 frame on the frame bars of the bed spring so as to support the device in spaced relation with respect to the mattress of the bed.

25 It will be seen that the device will form a complete housing for the occupant of the bed, and the screen material will prevent the entrance of flies and mosquitos. Obviously the device may be also used in wintertime, or during the cool period of the summer, the bedclothing being spread upon the top 5 of the quilt, the clothing thus being supported and maintained out of contact with the occupant of the bed, which of course would be very desirable when the occupant of the bed has recently undergone an operation for appendicitis and the like.

30 From the foregoing, it will be seen that I have provided a quilt or guard of this nature, which is simple in construction, inexpensive, strong, durable, practical, thoroughly reliable, and otherwise well adapted for the purpose designed.

35 Even though I have herein shown and described the preferred embodiment of my invention, it is to be understood that the same is susceptible to changes fully comprehended by the spirit of the invention and the scope of the appended claim.

40 Having thus described my invention, what I claim as new is:

45 55 In a foldable guard of the character described, a top section, end sections hingedly connected thereto, said top and end sections respectively formed of angle iron, side sections hinged to the top section, each of said 60 side sections being formed of relatively flat bars, said end sections adapted to fold inwardly toward one another with one flange of each of said end sections adapted to contact with a flange of the top section, and said side 65 sections adapted to fold inwardly over said

end sections for rest on the remaining flange of each of said end sections, said end and side sections when so folded being entirely confined within said top section.

70 In testimony whereof I affix my signature.

NOAH H. COLE.
